UNITED STATES PATENT OFFICE.

ORA O'BRIEN, OF HANFORD, CALIFORNIA.

AUTOMATIC FUEL-FEEDING MECHANISM FOR BURNERS.

1,093,878.

Specification of Letters Patent. Patented Apr. 21, 1914.

Application filed August 28, 1913. Serial No. 787,149.

To all whom it may concern:

Be it known that I, ORA O'BRIEN, a citizen of the United States, residing at Hanford, in the county of Kings and State of California, have invented certain new and useful Improvements in Automatic Fuel-Feeding Mechanism for Burners; and I do declare the following to be a full, clear, and exact description of the invention, such as 10 will enable others skilled in the art to which it appertains to make and use the same.

This invention relates to improvements in automatic fuel feeding mechanism for burners and particularly oil burners.

15 One object of the invention is to provide a fuel feeding mechanism for the burners of steam boilers which will be actuated by the pressure of the steam in the boiler thus automatically regulating or controlling the 20 flame and maintaining a steady uniform pressure in the boiler under all variations of the load.

Another object of the invention is to provide an automatically operated feeding 25 mechanism having an improved construction and arrangement of oil and steam controlling valves and an improved mixing chamber whereby the steam and oil are thoroughly commingled and discharged into the 30 fuel conducting pipe of the burner.

With these and other objects in view, the invention consists of certain novel features of construction, and the combination and arrangement of parts as will be more fully 35 described and claimed.

In the accompanying drawings: Figure 1 is a plan view of an improved fuel feeding mechanism; Fig. 2 is a side view thereof with parts broken away and in section; Fig. 40 3 is a central horizontal section of the same.

My improved fuel feeding mechanism comprises a double valve casing 1 in one side of which is an oil chamber 2 and in the opposite side a steam chamber 3. The 45 oil chamber 2 is provided with a threaded opening to receive an oil supply pipe while the chamber 3 is provided with an opening to receive a steam supply pipe, said oil and steam supply pipes not being shown in 50 the present instance. In the oil chamber 1 is formed an oil discharge passage 4 between which and the chamber 2 is arranged

a valve seat 5 with which is adapted to be engaged an oil controlling valve 7, the stem 8 of which works through a stuffing box 9 55 on the inner end of the oil chamber as shown.

The steam chamber 3 is provided with a steam discharge passage 10 between which and the chamber 3 is arranged a valve seat 60 11 with which is adapted to be engaged a steam controlling valve 12, the stem 13 of which works through a stuffing box 14 on the inner end of the steam chamber. The stem 8 of the oil valve 7 and the stem 13 65 of the steam valve 12 are adjustably connected at their outer ends to a cross head 15 to which is also connected the end of a valve operating rod 16, the opposite end of which is connected with an automatic controlling 70 mechanism hereinafter described.

The valve casing 1 has connected to its outer end a mixing chamber 17 in one side of which is a passage 18 which connects with the oil discharge passage 4 of the valve casing and in the opposite side of which is formed a steam inlet passage 19 which communicates with the steam discharge passage 10 of the valve casing, said passages 18 and 19 communicating with the mixing chamber 17. The mixing chamber 17 converges toward its outer end and has formed thereon an interiorly threaded socket 20 with which is adapted to be connected the fuel conducting pipe (not shown) which leads to 85 the burner. In the mixing chamber 17 is a transversely disposed partition 21, one side of which turns upwardly and is formed integral with the upper side of the chamber 17 adjacent to the oil inlet passage 18 while the 90 opposite side of the partition turns downwardly and is formed integral with the lower side of the chamber adjacent to the steam inlet opening 19. The outer portion of the partition 17 is arranged centrally between the upper and lower sides of the chamber 17 as clearly shown in Fig. 2 of the drawings. By thus arranging the partition 21, it will be seen that the oil coming into the chamber 17 through the passage 4 100 of the valve casing 1 and the passage 18 of the chamber 17 will enter the latter below the partition while the steam entering through the passage 10 of the valve casing

and the passage 19 of the chamber 17 will pass into the latter above the partition 21 and will commingle with the oil at the end of the partition and immediately before the 5 oil and steam leaves the chamber and enters the fuel conducting pipe.

Spaced a suitable distance from the valve casing 1 is an automatic valve controlling mechanism comprising a casing 22 which is 10 preferably attached to the casing 1 by a frame comprising upper and lower diverging bars 23 which are connected near the casing 1 by cross bars 24 as is clearly shown in Fig. 2 of the drawings. The casing 22 15 comprises a diaphragm chamber 25 and a spring chamber 26, said spring chamber communicating with the inner side of the diaphragm casing as shown. The outer portion of the casing 22 forming the diaphragm chamber 25 is constructed in the 20 form of a removable cap plate 27 between the outer edge of which and the adjacent outer portion of the body of the chamber is securely clamped the outer edge of a flexible 25 diaphragm 28. The cap plate 27 may be secured to the main body portion of the chamber 25 by clamping bolts 29 or other suitable means and in the center of the cap plate 27 is a threaded opening 30 with which is connected 30 the inner end of a steam pipe 31 which extends to and is connected with the boiler, heated by the burner to which the fuel is supplied from the mixing chamber 17 hereinbefore described.

35 In the outer end of the spring chamber 26 of the casing 22 is formed a threaded opening with which is engaged a tubular guide nut or plug 32 through which the rod 16 passes and is slidably supported. The rod 40 16 extends through the spring chamber 26 and into the diaphragm chamber 25 in which the end of the rod is connected with a flat head or disk 33, the outer surface of which is slightly convexed and engages the adjacent side of the diaphragm 28.

Arranged in the spring chamber 26 and engaging the inner end of the tubular guide nut 32 is a stop plate 34 having therein a central passage through which the rod 16 50 freely works. Arranged on the rod 16 between the stop plate 34 and the inner end of the diaphragm engaging plate 33 is a coiled spring 35, the pressure of which is exerted to resist the pressure of the steam applied to the 55 opposite side of the diaphragm 28 in the outer portion of the diaphragm chamber and to normally hold the oil valve 7 or steam valve 12 in the casing 1 open. By arranging the stop plate 34 at the inner end of the guide 60 nut 32 as herein shown and described, said nut may be arranged or employed for regulating the tension or pressure of the spring 35 by screwing the nut inwardly or outwardly to a greater or less extent in the

threaded opening of the spring chamber as 65 will be readily understood. The nut 32 thus serves a double function, to wit: The supporting and guiding of the valve operating rod 16 and the adjusting of the tension or pressure of the spring 35. By thus constructing and arranging the valve operating rod and the diaphragm 28, it will be seen that as the pressure of the steam in the boiler increases to a point where said pressure overcomes the tension or resistance of 70 the spring 35, the pressure of the steam against the diaphragm will depress the latter and project the head or disk 33 and the valve operating rod 16 thereby closing the oil and steam supply valves 7 and 12 to a 75 greater or less extent thus controlling the passage of the oil and steam to the mixing chamber and thereby regulating the flame and the amount of heat produced at the burner which, as will be readily understood, 80 will lower the temperature of the water in the boiler and reduce the pressure of the steam until the spring 35 is again permitted to expand and retract the valve operating rod thus again opening the valves to admit 85 a larger supply of fuel.

From the foregoing description, taken in connection with the accompanying drawings, the construction and operation of the invention will be readily understood without 95 requiring a more extended explanation.

Various changes in the form, proportion and the minor details of construction may be resorted to without departing from the principle or sacrificing any of the advantages of the claimed invention.

Having thus described my invention, what I claim is:

A fuel feeding mechanism for the burners of steam boilers comprising a double valve casing having in one side an oil chamber and in the opposite side a steam chamber, said chambers having discharge passages, valves to open and close said passages, stems connected with said valves, a valve operating rod, a yoke secured thereto and having an adjustable connection with the stems of said valves, a fuel mixing chamber connected with the discharge passages of said valve casing, a casing having therein a diaphragm chamber and a spring chamber, a diaphragm arranged in said diaphragm chamber, a steam pipe connected with said diaphragm chamber on one side of said diaphragm, a combined rod guiding and spring adjusting nut arranged in one end of said spring casing and adapted to receive and slidably support said valve operating rod in said spring casing, a head on said rod to engage said diaphragm, a stop plate in said spring casing and engaged with the inner end of said spring adjusting nut, and a spring arranged 115 between said plate and the head on said 120 125

valve operating rod and adapted to resist the pressure of the steam applied to the diaphragm whereby said valves are held open until the pressure of the steam against the diaphragm overcomes the resistance of said spring.

In testimony whereof I have hereunto set

my hand in presence of two subscribing witnesses.

ORA O'BRIEN.
